BICUSPID ORTHODONTIC BASE

Kozo Kawaguchi, Ohkuma-machi, Japan, assignor to
G.A.C. International, Inc., Farmingdale, N.Y.

Filed Apr. 30, 1975, Ser. No. 573,358

Term of patent 14 years

Int. Cl. D24—03

U.S. Cl. D24—1 C

FIG. 1 is a perspective view of the bicuspid orthodontic base showing my new design;

FIG. 2 is a top plan view of the orthodontic base of FIG. 1;

FIG. 3 is a side elevation view of the orthodontic base of FIG. 1;

FIG. 4 is a front elevation view of the orthodontic base of FIG. 1;

FIG. 5 is a rear elevation view of the orthodontic base of FIG. 1;

FIG. 6 is a cross-sectional elevation view taken along the line 6—6 of FIG. 2; and

FIG. 7 is a cross-sectional elevation view taken along the line 7—7 of FIG. 2.

I claim:

The ornamental design for a bicuspid orthodontic base, as shown and described.
